OYSTER OPENING APPARATUS

John L. Plock, Southold, N. Y.

Application January 30, 1946, Serial No. 644,265

3 Claims. (Cl. 17—9)

1

My invention relates to a method and apparatus for opening bivalves such as oysters and is an improvement over the invention of my application Serial Number 618,122 filed September 24, 1945. It has been customary to open such shells by inserting a knife blade between the two valves of a shell in order to cut the adductor muscle. This is a slow and difficult operation and requires a high degree of skill and frequently results in injury to the operator. My object is to simplify the process and make it easier, cleaner and safer so that oysters can be opened by almost any one at home or in small or large kitchens.

Accordingly instead of attempting to separate the valves by first breaking the shell and cutting the adductor muscle, I separate the two valves by turning one valve with respect to the other in the general plane of the meeting edges. This can be done in various ways but preferably by mechanism having jaws for engaging the opposite sides of the valves and turning or sliding one valve across the face of the other valve so as to twist the body of the oyster and tear the adductor muscle away from the left or deep valve and break the hinge. The adductor muscle is then easily cut away from the right or shallow valve with an oyster knife.

Fig. 1 is a side view on a small scale of one form of machine embodying my invention.

Fig. 2 is an edge view showing the approximate position of an oyster shell and the jaw members at the start of the opening operation.

Fig. 3 is a face view of the parts in the position of Fig. 2.

Fig. 4 is an edge view showing the relative positions of the jaws and the oyster shell when partially opened.

Fig. 5 is a plan view showing the relative positions of the oyster shell and the jaws corresponding to Fig. 2.

Fig. 6 is a view similar to Fig. 5 but with the shell swung around somewhat from the position of Fig. 5.

The drawing shows a typical oyster having the so-called deep or left valve 1 and the shallow or right valve 2. These valves are hinged together at 3 and connected by an adductor muscle 4.

To open the oyster, the shell is supported on the deep valve side and pressure is applied to the shallow valve in a plane generally or approximately parallel with the central plane passing through the edges of the valves so as to move the shallow valve across the face of the deep valve, shear the adductor muscle away from the deep valve and break the hinge. The oyster body is

2

then separated from the shallow valve by merely cutting the adductor muscle away from it by a very simple and easy movement of a knife.

To facilitate the separation of the parts of the shell, I have provided a frame 5 which has an elongated base 6 and a head 7 having arms 8 and 9 in which is guided a plunger 10. This plunger has a spring 11 interposed between the arm 9 and a shoulder 12 on the plunger so that the plunger is normally held in the upper position. The plunger can be depressed by use of the handle lever 13 which is hinged at 14 to the plunger and connected to the frame by a hinged link 15. A detachable U-shaped shield 16 extends around the front and sides of the arms 8 and 9 and encloses and protects the spring and plunger between the arms 8 and 9. The two jaw members 17 and 18 are detachably mounted on the base and on the plunger, respectively, jaw member 17 being secured by screws 19, 19 to the support 20 and jaw member 18 being secured to the plunger by a set screw 21. The lower jaw member 17 has a point 22 adapted to support the deep valve of the oyster as shown in the drawings. The upper jaw member 18 has a main point 23 adapted to engage the upper portion of the shallow valve as shown in the drawings and an auxiliary point 24. The jaw parts are so constructed and located that for good results the main upper jaw point 23 is approximately $\frac{1}{16}$ " in front of the lower jaw point 22 and approximately $\frac{3}{8}$ " to the left of point 22 (looking at the apparatus from the front). The auxiliary upper jaw point 24 is approximately in the same vertical plane as the main point 23 but about $\frac{1}{8}$ of an inch to the left as viewed in Figs. 3, 5 and 6.

To secure the best results, the face of the jaw member 18 against which the shallow valve is brought is preferably inclined at the approximate angle at which the shell is held and the opposite side of the jaw member has an abrupt shoulder close to the point 23. This construction facilitates the shearing action and prevents the moving jaw member from entering between the valves.

To open an oyster, it is held in the left hand and supported on the lower jaw point 22 in a position as shown in Figs. 2 and 3, the principal support being beneath the location of the adductor muscle, the adductor muscle being usually located in the center of the widest portion of the shell. The longitudinal axis of the shell is approximately horizontal and the shell held slightly inclined as shown in Fig. 2. The plunger is then depressed and the upper jaw member 18 brought down until the point 23 catches in a roughness of the shallow

valve of the shell above the adductor muscle location but a little further from the hinge joint than the support 22 is. The deep valve 1 being then supported vertically by the jaw member 17 and laterally by the hand of the operator, the upper jaw member is further depressed so as to apply pressure on the shallow member 2 sufficient to slide the latter across the face of the stationary valve as shown in Fig. 4, and thus shear the adductor muscle from the valve 1 and at the same time break the hinge 3.

Fig. 5 shows the usual position of the shell when being operated on, inclined slightly to the face of the jaw member 17. In case the point 23 does not quickly catch in a rough spot on the valve 2, 15 the shell can be turned and tilted slightly to the position of Fig. 6 whereupon the auxiliary point 24 will take hold and enable the operator to complete the opening of the shell.

Although the present apparatus is intended to be portable it may be supported on a wall if desired. The exact design is immaterial to the invention as herein described.

The apparatus may also be advantageously used to separate oysters which may be secured together in a cluster as they frequently are. In such cases, the points of the jaws are applied at rough parts of the respective shells and then one jaw is moved toward the other so as to force the shells apart.

Very few people are able to open oysters in the usual way and as a result the householder feels obliged to buy already opened oysters. In fact a great many smaller restaurants and dining rooms are unable to use oysters in the shell for the reason that they have no one who is able to open oysters in the usual way by hand. My invention is so simple and the apparatus so easy to operate that any one can be taught to use the apparatus in a few moments thus making it possible and convenient for a general and wide use of oysters in the shell to be opened at home or in any restaurant or kitchen.

Prior art patents show apparatus for opening oyster shells involving the use of a knife or knives for entering between the valves and cutting the oyster from one of the valves in a manner likely to injure the meat of the oyster. In contrast with such mechanism and methods I provide apparatus by which the valves are separated without the use of a knife and without touching the meat. In fact the movable jaw member is formed with an abrupt shoulder alongside of its gripping prong which in case the prong should slip will prevent the prong from entering between the valves to injure the meat.

I claim:

1. A machine for opening oyster shells comprising a frame having a stationary jaw member constituting an abutment for supporting the outer face of the deep valve of an oyster shell between the ends thereof but leaving a free space alongside of the abutment to allow for the free movement of the shallow valve of the oyster across the face of the deep valve when the latter is supported by the abutment, a movable jaw member having a short prong for engaging the outer face of the shallow valve of the oyster which is supported on the abutment and having a shoulder adjacent said prong for preventing the said movable jaw member from entering between the edges of the shell and means for moving the movable

jaw member against the outer face of the shallow valve when the shell is supported between the ends of the shell and thereby moving the shallow valve across the inner face of the deep valve and tearing the adductor muscle from the deep valve without entering between the valves.

2. A machine for opening oyster shells comprising a frame having a stationary jaw member forming an abutment for supporting the outer face of the deep valve of an oyster between the ends thereof but leaving a free space alongside of the abutment to allow for the free movement of the shallow valve of the oyster across the face of the deep valve when the latter is supported by the abutment, a movable jaw member having two short prongs spaced apart from each other for engaging the outer face of the shallow valve of the oyster which is supported on the abutment, said movable jaw member having a transverse shoulder near the prongs for preventing the movable jaw member from entering between the edges of the shell and means for moving the movable jaw member with its prongs against the outer face of the shallow valve between the ends of the shell in a direction out of alignment with the stationary jaw member and thereby moving the shallow valve across the inner face of the deep valve and tearing the adductor muscle from the deep valve without entering between the valves.

3. A machine for opening oyster shells comprising a frame having a base, a stationary jaw member on the base, said jaw member having an upwardly projecting portion with one of its side surfaces tapering upwardly and outwardly to form a short prong, a plunger movably carried by the frame above said stationary jaw member, an integral head on the lower end of said plunger having a portion of its side face tapered downwardly and inwardly, the tapered portion of said head extending downwardly to form a prong offset laterally and forwardly from the prong of the stationary jaw member, said jaw members being normally spaced apart a distance sufficient to receive an oyster shell held therebetween in vertical position with the lower face of the deep valve of the oyster impinged upon the prong of the stationary jaw member and with the upper face of the shallow valve of the oyster in line with the path of movement of the prong of the movable jaw member whereby the shallow valve may be sheared off of the deep valve upon downward movement of the plunger.
